Edward A. Bazzett

By Samuel Williston, M.D.

UNITED STATES PATENT OFFICE.

EDWARD A. BAZZETT, OF ROCHELLE, ILLINOIS.

CLOCK.

No. 908,938.

Specification of Letters Patent.

Patented Jan. 5, 1909.

Application filed March 21, 1907. Serial No. 363,574.

To all whom it may concern:

Be it known that I, EDWARD A. BAZZETT, a citizen of the United States, residing at Rochelle, county of Ogle, State of Illinois, 5 have invented a certain new and useful Improvement in Clocks, and declare the following to be a full, clear, and exact description of the same, such as will enable others skilled in the art to which it pertains to 10 make and use the same, reference being had to the accompanying drawings, which form a part of this specification.

My invention relates in general to clocks, and more particularly to means for securing 15 the works of small clocks within supporting frames.

In the manufacture of small clocks having supporting frames it is usual to provide 20 means for securing the works within a casing separate from the pillars which unite the plates between which the movement is mounted, and to also provide fastening means for securing the casing to the supporting frame. It is also usual to provide 25 flanges for over-lying the outer surfaces of the supporting frames separate from but secured to the casings which inclose the works.

The primary object of my invention is to 30 provide a clock and supporting frame therefor which will require but a single set of fastening devices for connecting the plates of the movement, for securing the works within the casing, and for attaching the 35 casing to the supporting frame.

A further object of my invention is to provide a casing for clocks having formed integrally therewith a flange for engaging the front surface of a supporting frame.

40 A still further object of my invention is to provide a clock and a supporting frame therefor which will be simple in construction, inexpensive in manufacture, and efficient in use.

45 My invention as herein disclosed may be generally described as comprising works having plates between which the movement is supported, an inclosing casing having an integral flange over-lying the front 50 surface of the frame, a supporting frame, a removable back for the supporting frame, rods uniting the plates of the works and extending through holes in the casing and back plate of the frame, and series of nuts 55 on the rods engaging the back plate of the

works, the outer surface of the casing, and the outer surface of the back plate of the frame.

My invention will be more fully described hereinafter with reference to the accompanying drawings in which the same is illustrated as embodied in two convenient and practical forms, and in which:

Figure 1 is a front elevational view; Fig. 2 a rear elevational view; Fig. 3 a cross-sectional view on line 3—3 Fig. 1; Fig. 4 a perspective view of the casing; Fig. 5 a perspective view of the back plate of the frame; Fig. 6 a front elevational view of a modified form of my invention; Fig. 7 a rear elevational view of the modification shown in Fig. 6; Fig. 8 a vertical view on line 8—8 Fig. 6; and Fig. 9 a perspective view of the back plate of the supporting frame.

75 Similar reference characters are used to designate similar parts in the several figures of the drawings.

Referring more particularly to Figs. 1 to 5 inclusive, reference letter A designates a 80 supporting frame for a clock which may be made of any suitable material and of any desired design.

a, a indicate the feet of the supporting frame adapted to rest upon a supporting 85 surface.

B designates a casing for inclosing the works, such casing being formed integrally and comprising a circular back wall and cylindrical side wall. An outwardly projecting flange b surrounds the open end of the casing and is adapted to overlie the front surface of the frame.

C' and C² designate the usual plates of the works of a clock between which the 95 movement is supported. The movement is not shown as it forms no part of my invention.

C designates the dial which is supported upon the front plate C² by means of studs c. 100

D indicates the beveled crystal which is secured within the open end of the casing B by means of a bezel E having a cylindrical flange fitting within the casing and an inwardly projecting flange e overlying 105 the periphery of the crystal.

F designates a reflector which is interposed between the crystal and the dial so as to symmetrically space the crystal and dial apart.

110

G', G², and G³ designate rods interposed between the plates C' and C² for supporting the same in parallel relation. Each of these rods is of a greater diameter between the 5 plates than the portions which extend through the plates, thereby forming shoulders against which the inner surfaces of the plates engage. The reduced ends of the rods which extend through the plate C² constitute 10 the posts e for supporting the dial. The reduced portions of the rods which project through the plate C' are screw-threaded to be engaged by nuts. A nut g' engages each of the rods and bears against the outer surface 15 of the plate C' thereby securing the same in a fixed relation with respect to the front plate C². The screw-threaded portions of the rods extend through holes in the circular rear wall of the casing B and are provided 20 with nuts g² which engage the rear surface of the casing and clamp the same against the nuts g' thereby supporting the works within the casing.

The screw-threaded portions of the rods 25 G', G², and G³ also extend through holes in a back plate H of the supporting frame and are provided with nuts g³ engaging the outer surface of such plate. The back plate H is preferably concave and is provided with an 30 outwardly projecting flange h which overlies the rear surface of the supporting frame. The nuts g³ consequently through their engagement with the rods draw the flange h on the casing against the front surface of 35 the frame and simultaneously draw the flange h on the back plate against the rear surface of the frame, thereby tightly securing the casing within the frame.

In Figs. 6 to 8 inclusive I have illustrated 40 my invention as applied to a clock having a modified form of supporting frame. In this modification reference character A' designates a supporting frame in the form of a plate having feet a', a'' for supporting 45 the bottom thereof. The casing with the works therein extends through an opening in the frame A' so that the flange b' around the casing will overlie the front surface of the frame. H' indicates the back plate of 50 the frame which is in the form of a cylinder having a circular back wall and cylindrical side walls and provided with an outwardly projecting flange h' around its open end which overlies the rear surface of the frame 55 A'. The screw-threaded portions of the rods G', G², and G³ extend through holes in the rear wall of the supporting plate H' so that the nuts g³ serve to force the flange h' tightly against the inner surface of the 60 frame and simultaneously draw the flange b' on the casing tightly against the outer surface of the frame. a² indicates a leg for supporting the frame at the rear thereof, such leg being secured to the frame by means 65 of a hole in the upper end thereof through

which the screw-threaded end of the rod G' projects, a nut g⁴ being provided on such rod for clamping the upper end of the leg against the nut g³ on such rod.

From the foregoing description it will be observed that I have invented an improved 70 clock and supporting frame therefor, in which the same fastening devices secure the plates which support the works together, support the works within the casing, and 75 secure the casing to the supporting frame. It is evident that by my improvement the works may be readily secured within the casing and the casing easily secured to the supporting frame. It will also be observed 80 that my improved casing is provided with an integral flange for overlying the front surface of the frame, thereby avoiding the necessity of providing a front flange separate from the casing. 85

While I have described more or less precisely the details of construction, I do not wish to be understood as limiting myself thereto, as I contemplate changes in form, the proportion of parts, and the substitution of equivalents, as circumstances may suggest or render expedient without departing from the spirit of my invention. 90

Having now fully described my invention, what I claim as new and desire to 95 secure by Letters Patent is:

1. In a clock, an inclosing casing having a shoulder thereon; a frame bearing on one side against said shoulder; a back-plate bearing against the opposite side of 100 the frame to hold it against said shoulder; bolts passing through said back-plate and projecting through the rear of the casing, nuts on said bolt for tying the bolts the back-plate and the casing together and 105 clamping the frame between the shoulder on the casing and the back-plate; and clock-work arranged within the casing and supported wholly upon the free ends of the bolts. 110

2. In a clock, an inclosing casing having an outwardly projecting shoulder near the front end thereof; a frame surrounding the casing and engaging with said shoulder on the rear side thereof; a back-plate having a 115 shoulder arranged in rear of and engaging with said frame; bolts passing through said back-plate and the rear wall of the casing and projecting into the interior of the casing; a plurality of nuts on said bolts for 120 tying the back-plate and the casing rigidly together and at the same time clamping the frame between the shoulder on the casing and the shoulder on the back-plate; and supporting plates for a clock-work arranged 125 within said casing and supported wholly upon the free ends of said bolts.

3. In a clock, an inclosing casing having an exterior shoulder near the front thereof; a frame surrounding the casing and bearing 130

against the shoulder on the rear side thereof, a back-plate provided with a shoulder engaging with the rear face of the frame; a bolt passing through said back-plate and 5 the rear wall of the casing and projecting into the interior of the casing; nuts on said bolt for tying the rear wall of the casing, the back-plate and the bolt together and at the same time clamping the frame between 10 the shoulder on the casing and the shoulder on the back-plate; supporting plates for a clock-work arranged within said casing and supported wholly upon the free end of the bolt; and a dial supported by said bolt near 15 the front end of the casing.

4. A clock casing comprising an outer casing or frame, an inner casing having

means to prevent the passage of the inner casing through the outer casing, a back plate, bolts or posts for carrying the clock- 20 works passing through the back of the inner casing and the back plate, the said bolts having shoulders resting against the back of said inner casing and means carried by the posts for drawing together and holding 25 the inner and outer casings and the back plate.

In testimony whereof, I sign this specification in the presence of two witnesses.

EDWARD A. BAZZETT.
